CLAIM

The ornamental design for a hydroponic planter, as shown and described.

DESCRIPTION

FIG. 1 is a perspective view of a hydroponic planter, taken from the front.

FIG. 2 is a front view of the hydroponic planter of FIG. 1. FIG. 3 is a back view of the hydroponic planter of FIG. 1. FIG. 4 is a left-side view of the hydroponic planter of FIG. 1.

FIG. 5 is a right-side view of the hydroponic planter of FIG. 1.

FIG. 6 is a top view of the hydroponic planter of FIG. 1; and, FIG. 7 is a bottom view of the hydroponic planter of FIG. 1. The dashed broken lines depict portions of the hydroponic planter which form no part of the claimed design.

1 Claim, 7 Drawing Sheets
